UNITED STATES PATENT OFFICE.

CHARLES WHITTINGHAM, OF CLEVELAND, OHIO, ASSIGNOR TO THE CLEVELAND FOUNDRY COMPANY, OF SAME PLACE.

DESIGN FOR AN OIL-STOVE.

SPECIFICATION forming part of Design No. 24,115, dated March 12, 1895.

Application filed December 14, 1894. Serial No. 531,859. Term of patent 7 years.

To all whom it may concern:

Be it known that I, CHARLES WHITTINGHAM, a citizen of the United States, residing at Cleveland, in the county of Cuyahoga and State of Ohio, have invented and produced a new and original Design for an Oil-Stove, of which the following is a specification, reference being had to the accompanying drawing, showing a part thereof.

10 In the accompanying figure, I have illustrated my design of an oil stove in a front perspective view, looking downward somewhat and exhibiting the stove at about the same angle as would occur to one looking at it from a fairly near point of view. Thus presented, we have, as the more conspicuous features of the design, the appearance about the lower portion of the stove and comprising the distinctly base portion with its plain annular 15 part —2— surmounted by an outstanding ring shaped foot rest —3—, and the cylindrical body —4— of the top part of the stove having a figured border —5— about its base and sup-

ported independently on the annular base part —2— and apart therefrom on supports 25 —6—. The border —3— is perceptibly smaller in cross section than the part —2— beneath so as to give symmetry to the structure and stands up above the plane of the ring —3—.

The design therefore comprises the stove as shown and as a whole, but with the parts hereinbefore particularly described as its leading and distinguishing features, when said parts are arranged and have the appearance collectively substantially as herein set forth.

Having thus described my invention, what I claim as new, and desire to secure by Letters Patent, is—

The design for an oil stove substantially as herein shown and described.

CHARLES WHITTINGHAM.
